UNITED STATES PATENT OFFICE.

JAMES MURRAY WASHBURN, OF CHICAGO, ILLINOIS.

DESIGN FOR A HOLDER OR SUPPORT FOR CARDS, PICTURES, AND THE LIKE.

45,845.

Specification for Design.

Patented May 26, 1914.

Application filed December 15, 1913. Serial No. 806,926. Term of patent 14 years.

To all whom it may concern:

Be it known that I, JAMES MURRAY WASHBURN, a citizen of the United States, residing at Chicago, in the county of Cook, State of Illinois, have invented a new, original, and ornamental Design for a Holder or Support for Cards, Pictures, and the like, of which the following is a specification, reference being had to the accompanying drawing, forming a part thereof.

The figure is a plan view of a holder or support for cards, pictures and the like showing my new design.

I claim:

The ornamental design for a holder or support for cards, pictures and the like, substantially as shown.

JAMES MURRAY WASHBURN.

Witnesses:

WALLACE R. LANE,
CLARENCE J. LOFTUS.
